UNITED STATES PATENT OFFICE.

CHESTER THOMAS MCGILL, OF ELGIN, ILLINOIS. ASSIGNOR TO REITER CO., OF ELGIN, ILLINOIS, A CORPORATION OF ILLINOIS.

SYSTEM FOR REMOVING IMPURITIES FROM STEAM BOILERS.

Application filed April 18, 1925. Serial No. 24,233.

This invention has for its prime object the removal of impurities from a horizontal return tubular type of steam boiler while in operation, or any other type of boiler, 5 without the use of pumps or other special machinery.

It is a practice to test and treat boiler feed water while the boiler is in operation by means of some system of softening and 10 purifying boiler water, whereby the various impurities are placed in suspended form so that they can be more easily removed, preferably in the manner described and claimed in this application.

15. An object of this invention is to remove all impurities from various kinds and types of steam boilers, by means of a circulating and precipitating system for the boiler water, consisting in general of a precipitating tank, pipes, valves and fittings, so arranged that the proper amount of water is circulated through the system continuously to carry all suspended matter of every kind with the water from the boiler and deposit 20 it in the precipitator where it may be blown out into the sewer or otherwise disposed of.

Another object of this invention is to provide a method and apparatus whereby the boiler may be kept clean during operation 30 of the plant, by removing the impurities from the boiler water while the boiler is under steam.

In the drawings:—

Fig. 1 designates the circulating system 35 in an assembled form, as connected to an ordinary boiler.

Fig. 2 is an elevation view of the lower section of the precipitator tank, showing the arrangement of valves and pipes attached thereto.

The numerals 1 and 2 designate the surface and bottom water supplies within an ordinary boiler of a suitable type, while the numeral 3 represents a precipitator tank, 45 located at a convenient point with respect to the boiler. The numeral 4 designates the return pipe line as a whole leading from the precipitator tank to the boiler, while 5 is the main blow off valve from the precipitator. 6 designates the blow off valve in the pipe leading from the surface or top of precipitator 3, the numeral 7 represents the final blow off valve controlling the discharge to the sewer or otherwise.

55. A valve 9 is located between the return

line portions 33 and 26 from the precipitator 3. Numeral 10 designates the automatic air trap, while 11 and 12 are pipe connections, and 13 and 14 designate supply line fittings.

The numeral 15 represents the pipe connections to the air trap 10, and 16 the air cushion pipe and cap, while 17 refers to the air trap valve, 18 and 19 are pipe nipples, and 20 is an extra heavy connection to the precipitator tank. The numeral 21 designates a special T fitting with a blind end, while 22 represents the nipple stand, and 23 the floor plate for the tank. The surface blow down line from the precipitator is represented by the numeral 24, and 25 is a cross connection therefrom, while 26 is lowermost portion of the return connection to the boiler. The supply line 27 to the system has a special pipe fitting 28 inside the boiler to accommodate the surface supply and bottom 75 supply pipes, 1 and 2.

The numeral 29 designates a sleeve for covering the return portion of the pipe line 4, while 30 is a vent pipe from air trap 10, and 31 is a water sample valve. The valve in the pipe leading from the air trap 10 is represented by numeral 32, while 33 designates the upper portion of the return pipe line from the precipitator 3 to the boiler.

In operation the water is supplied to the boiler in the usual manner from the source of supply. During the process of feeding and heating, the water is tested and treated, thereby placing the impurities in a suspended form so that they may be readily handled by this invention. The procedure is carried out in general by first noting that valves 17, 6, 31 and 32 are opened, then opening valve 9 until the precipitating tank fills with boiler water. The air contained in the precipitator 3 is dislodged through the pipes controlled by valves 6, 17, 32, and 31, also pipe 30. When the air is all out close valves 6, 31 and 32. Valve 8 may then be opened and the system is in operation. Valves 8 and 9 are wide open during the operation of the system.

The system is supplied with water through pipes 1 and 2 inside of the boiler. The water returns from the precipitator 3 back to the boiler through the line controlled by valve 9. The arrows indicate circulation. The light flocculent matter is drawn off through the line controlled by valves 6 and 7 to the sewer or through the line controlled 110

by valves 6 and 31 to a pail or other receptacle. The heavy sediment, soft lime or other residue may be drawn out from the precipitator 3 through the line controlled by valves 5 and 31 into a pail or other receptacle, or may be blown into the sewer through the line controlled by valve 7.

This invention particularly provides a means consisting of a combination with a boiler structure of a system for removing impurities from the water thereof, said system comprising a precipitator, a pipe extending from the boiler to the precipitator and having one end arranged below the normal water level in the boiler and its second end disposed in the precipitator and a return line arranged to convey purified water from the precipitator to the boiler and including a portion inclined upwardly, through the combustion chamber toward the boiler shell and a shield surrounding the upwardly inclined portion and spaced therefrom and communicating with the interior of the combustion chamber.

It is apparent from the above description, that by taking samples from the top of the precipitator, the bottom of the precipitator and from the air trap line, an indication may be obtained as to how well the precipitator has removed certain solids and in what proportions it has reduced the concentration of suspended, as well as soluble matter. Also, by taking the samples from the bottom of the precipitator, an indication is obtained as to how well the precipitator has functioned and, of course, these samples have considerable to do with what the next step of the operator would be in properly conditioning the water in the boiler. Obviously, the sample taken from the air trap line is the same as the water in the boiler and indicates the condition of the boiler water and the kind of sediment to be removed in the precipitator.

In this connection, it may be further stated that the water which is ordinarily supplied direct to the boiler, would carry so many grains of hardness per gallon that a portion of the scale forming solids would be neutralized and precipitated by the heat, the remaining solids being neutralized by chemical treatment.

Knowing the amount of evaporation in a boiler and the hardness contained in the water and the amount of treatment required for each one thousand gallons of water, it is known definitely how much sediment and solids are to be removed by the system according to this invention. In other words, it is known within a very close approximation the number of pounds of solids the system will remove hourly from the boiler. These solids are usually blown to the sewer without any measuring of the solids; however, they can be drawn off in a pail or bar-

rel and it can be determined quite accurately whether all the solids are being removed.

By taking a sample of water from the air trap line through valves 32 and 31, it enables the operator to tell definitely the condition of the water as it travels from the boiler to the precipitator. By testing this water, it indicates whether the water is soft, the amount and kind of treatment in excess, and whether the water is carrying a sufficient amount of sediment to keep the boiler clean. In every water there is light flocculent matter which has a lighter specific gravity than the water itself. These solids are accumulated at the top of the precipitator out of the regular current or travel of the water and by drawing water off through line 24 and valves 6 and 31 for test purposes, indicate whether this end of the precipitator is getting as much of these light flocculent solids as it should get hourly.

Then taking samples from the bottom of the precipitator through line 20 and valves 5 and 31 indicates whether the bottom portion of the precipitator is functioning efficiently and removing all of the sediment that have a heavier specific gravity than the water.

The operator soon gets to the point where, as soon as he draws a sample from any of these three places, he knows fairly well what results are being obtained at the other two points. For illustration:—a sample of water taken from the air trap through the line controlled by valves 32 and 31, would indicate the amount of sediment being carried in circulation to the precipitator and would indicate whether this sediment settled out readily at the bottom or accumulated at the top of the sample. In this way, without making any further tests, he can be guided in just what to do to further condition the water in the boiler. In doubtful cases, the samples from the top of the precipitator and the bottom of precipitator will indicate the proper procedure to take.

What I claim is:—

1. The combination with a boiler structure, of a system for removing impurities from the water thereof, said system comprising a precipitator, a pipe extending from the boiler to said precipitator and having one end arranged below the normal water level in the boiler and its other end disposed in the precipitator, a return line arranged to convey purified water from said precipitator to the boiler and including a portion inclined upwardly through the combustion chamber toward the boiler shell and a shield surrounding the upwardly inclined portion and spaced therefrom and communicating with the exterior of the boiler wall and the interior of the combustion chamber.

2. The combination with a boiler structure of a system for removing impurities

- from the water thereof, said system including a precipitator, a discharge line projecting upwardly from a point below the normal water level of the boiler, a pipe extending 5 upwardly from said precipitator, a pipe inclined upwardly from the discharge line to the first mentioned pipe, a return line arranged to convey purified water from the precipitator to the boiler and including a 10 portion inclined upwardly through the combustion chamber toward the boiler, and a shield surrounding the inclined portion and spaced therefrom and communicating respectively with the exterior of the boiler 15 wall and the interior of the combustion chamber.
3. In a boiler water purifying system, the combination of a precipitator, a pipe extending upwardly therefrom, an air trap 20 communicating with the upper portion of said pipe, a conduit connected to said pipe between said precipitator and trap, a blow off line leading from said precipitator, said trap including sedimentation chamber, and 25 a valved pipe connecting said air trap sedimentation chamber with the blow-off line from said precipitator.
4. In a boiler water purifying system, the combination of a precipitator, a pipe extending upwardly therefrom, an air trap 30

communicating with the upper portion of said pipe, a conduit connected to said pipe between said precipitator and trap, a blow-off line leading from said precipitator, said trap including sedimentation chamber, and 35 a valved pipe connecting said air trap sedimentation chamber with the blow-off line from said precipitator, and means communicating with the valved pipe for removing samples therethrough from the chamber. 40

5. In a boiler purifying system, the combination of a precipitator, a pipe extending upwardly therefrom, an air trap communicating with the upper portion of said pipe, a supply line leading from the boiler to the 45 top of the precipitator, a return line from the precipitator to the boiler and means for removing samples of water from the top of the precipitator, the bottom of the precipitator and from the air trap, thereby making 50 it possible to note the efficiency of the precipitator, and in what proportions it has reduced the concentration of suspended, as well as soluble matter, the means for removing samples from the top and bottom of the 55 precipitator being adapted to draw off the impurities which accumulate.

In testimony whereof I affix my signature.

CHESTER THOMAS McGILL.
